(57) **CLAIM**

The ornamental design for a first aid kit, as shown and described.

DESCRIPTION

FIG. 1 is a front isometric view of a first aid kit showing the new design in a closed state;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front environmental view thereof showing the first aid kit in an opened state.

The broken line showing of the first aid kit is for the purpose of illustrating portions of the first aid kit that form no part of the claimed design.

1 Claim, 8 Drawing Sheets
